UNITED STATES PATENT OFFICE.

HAROLD MASON CHASE AND GEORGE WILMOT ROBERTSON, OF DANVILLE, VIRGINIA,
ASSIGNORS TO RIVERSIDE AND DAN RIVER COTTON MILLS, INC., OF PITTSYLVANIA
COUNTY, VIRGINIA, A CORPORATION OF VIRGINIA.

WARP-DYEING APPARATUS.

Original application filed December 5, 1922, Serial No. 605,032. Divided and this application filed September 29, 1923. Serial No. 665,722.

To all whom it may concern:

Be it known that we, HAROLD MASON CHASE and GEORGE WILMOT ROBERTSON, citizens of the United States and residents of 5 Danville, in the county of Pittsylvania and State of Virginia, have invented certain new and useful Improvements in Warp-Dyeing Apparatus, of which the following is a specification.

10 Our present invention relates generally to apparatus for treating cotton threads in the form of long chain warps and more particularly to apparatus for dyeing long chain warps, our present application being a division 15 of our application Serial Number 605,032 which was filed December 5, 1922.

More especially our invention has to do with the continuous dyeing of warps or in other words to a machine wherein the dye 20 is maintained in approximately full strength by the intermittent or regular addition of dye stock as distinguished from those in which the warps gradually use up the dye in the first passage therethrough and are 25 then reversed and passed through a second dye bath in order to render their color uniform throughout, our primary object being the provision of a dyeing machine by means of which uniform results may be easily obtained 30 in a continuous run apparatus.

It is for the above reasons that our invention proposes the successive dipping of the warps in the same dye chamber in such manner that they are subjected to the same 35 dye liquid at each dip and are oxidized to render the dye insoluble after each dip.

In the accompanying drawings, illustrating our present invention and forming a part of this specification,

40 Figure 1 is a sectional side view of our improved dyeing machine, and,

Figure 2 is a top plan view thereof.

According to our invention, we provide a dye vat 15, downwardly into which at one 45 end the warps pass in practice around a guide roller 52 and it is to be particularly noted that this dye vat has a single internal compartment provided with two sets 53 and 54 of internal warp guide rollers. As the

50 rope warps pass downwardly into one end of the tank they proceed to the lower end of the set 53 of guide rollers and have a circuitous path around these rollers and up-

wardly through the dyestuff, the latter being in constant agitation and circulation by 5 a series of agitators 55 in the form of paddles secured upon transverse shafts 56 whose opposite ends project beyond opposite sides of the vat. These shafts 56 have at one side of the vat sprockets 57 connected by sprocket chains 58 so that the several shafts 56 with their agitators 55 rotate in unison, the shaft 56 near the intake end of the vat having at its opposite end a sprocket 59 around which the lower end of a 60 sprocket chain 60 extends.

After their circuitous travel around the guide rollers of the first set 53 of the dye vat, the rope or chain warps pass around a guide roller 61 and between squeeze rolls 70 62, of which the lowermost roll has a gear 63 engaging the gear 64 of a countershaft 65, this countershaft having a sprocket 66 around which the upper end of the agitator driving chain 60 extends, and is also 75 provided with a sprocket 67 around which a driving sprocket chain 42 extends.

The shaft of the lower squeeze roll 62 also has a sprocket 68 from which a sprocket chain 69 leads. Upon their passage between the squeeze rolls 62 where the surplus dye liquid of the first dip is removed, the warps pass upwardly and for a considerable space around oxidizing reels 70 during which the dyestuff resulting from the first dip becomes 85 oxidized so that the warps may again pass downwardly into the dye vat around a guide roller 71 to the lower portion of the second set 54 of internal guide rollers. The warps take a circuitous path upwardly around 90 these guide rollers of the second set 54 and from the top of this set pass over a guide roller 72 and between squeeze rolls 73 of which the lower roll has a sprocket 74 driven by the sprocket chain 69 beforementioned. In this way the surplus dye liquid of the second dip is squeezed from the chain warps and these warps then pass upwardly for a considerable distance around oxidizing reels 75 and during such passage the dye accumulated during the second dip is oxidized and rendered insoluble.

100 This completes the dyeing apparatus and it is to be particularly noted in connection with the dye vat itself that we provide for two separate dips of the warps into the 105

same dye chamber and the same dye liquid with the latter at all times in agitation and circulation through the use of the agitators 55, the warps passing between squeeze rolls 5 and over oxidizing reels at the end of each dip so that by the intermittent or regular introduction of dye stock within the vat we insure uniform coloring of the warp without waste of dye stock and without the use 10 of expensive apparatus which would necessarily be employed for maintaining separate dye vats in uniform condition with doubtful results.

Furthermore by providing for successive 15 dips of the warps in the same dye vat we have not only accomplished the advantages hereinbefore set forth from a mechanical standpoint, but we have furthermore rendered this operation certainly uniform 20 which is essential to the success of a continuous apparatus of this nature.

We claim:

1. In a warp treating apparatus, a warp dyeing machine including a single dye 25 chamber having means for separate, suc-

cessive movements of warps therethrough, and having squeeze rolls and oxidizing devices for the warps after each movement thereof through the dye chamber.

2. In a warp treating apparatus, a warp 30 dyeing machine including a single dye chamber having means for separate, successive movements of warps therethrough, and having squeeze rolls and oxidizing devices for the warps after each movement thereof 35 through the dye chamber, and means for continuously agitating the dye material in said dye chamber.

3. In a warp dyeing apparatus, a tank having a single chamber for the dyestuff, 40 separate sets of warp engaging rollers within said chamber, guide rollers on the tank for guiding the warps to said sets of rollers, oxidizing reels over which the warps pass from each set of tank rollers, and squeeze 45 rolls through which the warps pass from each set of tank rollers, as described.

HAROLD MASON CHASE.
GEORGE WILMOT ROBERTSON.
